(57) **CLAIM**

The ornamental design for a “weighing scale for babies,” as shown and described.

DESCRIPTION

FIG. 1 is a top, left, front perspective view of a weighing scale for babies;

FIG. 2 is a top plan view thereof;

FIG. 3 is a bottom plan view thereof;

FIG. 4 is a front view thereof;

FIG. 5 is a rear view thereof;

FIG. 6 is a left side view thereof; and,

FIG. 7 is a right side view thereof.

The broken line showing is for illustrative purposes only and forms no part of the claimed design.
